UNITED STATES PATENT OFFICE

GEORGES CUTTAT, OF PARIS, FRANCE, ASSIGNOR TO SOCIÉTÉ ANONYME DES ÉTABLISSEMENTS CUTTAT, OF PARIS, FRANCE

HYDRAULIC PUMP AND MOTOR

Application filed July 17, 1928, Serial No. 293,407, and in France April 18, 1928.

The present invention has for object a system of multi-cylinder hydraulic pump or motor having fixed or rotary cylinders in which the reciprocating stroke of the pistons is controlled by an eccentric.

The system in accordance with the invention is essentially characterized in that:

1. It allows of varying—in reverse ratio to each other—the pressure and the outflow for a constant driving torque applied to the driving shaft.

2. It comprises a device for guiding the pistons in their cylinders, specially devised in view of diminishing, in a large proportion, the reaction of the first ones on the second ones and, consequently, of reducing the friction and wear resulting from this reaction. This guide device can moreover be applied to any motor or pump in which the reciprocating movement of the pistons is effected by means other than an eccentric.

In accordance with the invention, in the systems of pumps or motors of the type under consideration:

25 (a) The variation of the cylinder charge is determined by variation of the length of the stroke of the pistons in the respective cylinders. This variation is obtained by the combination of two eccentrics, viz: a first eccentric carried by the fixed shaft and a second eccentric movable and adjustable on the first one by means of a manual control or by an auxiliary motor. These two eccentrics are so devised that, from a position corresponding to the maximum eccentricity, one-half revolution of the eccentric movable on the fixed eccentric, brings back this eccentricity to zero, by passing through all the intermediate values;

40 (b) The distribution is ensured by a rotating distributing member accompanying the movable eccentric in its angular movement about the fixed eccentric.

45 This arrangement ensures the necessary continuity of the distribution as, during this displacement, the point of eccentricity, by varying from its "maximum" position to its "minimum" position (or vice versa) moves

50 according to a spiral curve and not rectilin-

early according to the axis of the fixed shaft.

In these conditions, the dead centers which correspond to the moments of change of direction of the distribution move by accompanying the movement of the movable eccentric. As far as this point is concerned, the system in accordance with the invention advantageously differentiates from other known systems having also an adjustment of the eccentricity by rotation—but in which the distributor is not displaced at the same time as the adjustable eccentric. In these known systems, the adjustment of the distribution is destroyed every time the eccentricity is varied, so that the operation of such apparatus cannot be satisfactory.

Moreover, apparatus in accordance with the invention, may not comprise any valve or equivalent element; in these conditions, the system is reversible and has this advantage that it is capable of operating as well as a motor as a pump.

(c) Each of the links ensuring the transmission of the movement of the driving eccentric to the pistons (double adjustable eccentric defined at (a), or even simple non-adjustable eccentric) is connected to a small guide link holding the corresponding link in a position approximately parallel to the radius starting from the center of the driving shaft and passing through the axis of the corresponding piston; for that purpose, each small link is pivoted on the frame of the pistons by its end opposite to that which receives the link.

(d) For a form of construction which will be more particularly described, the eccentric is in the shape of a circular raceway in which the small links fit at their respective pivoting points.

At these points, rollers rigid with the small link constantly follow the raceway, so that the control of each of the pistons is positive, as well during the suction cycle as during the compression cycle; the raceway is mounted on the eccentric through the medium of ball or roller bearings or equivalent systems.

The shape of the raceway may be varied

according to the modes of construction. The invention comprises moreover the assemblages in which the raceway controls each piston only during the compression 5 cycle, the return movement being then ensured by any suitable device, if it is necessary to positively control the said return movement.

The description which will be given here- 10 inafter by way of example, with reference to the accompanying drawings, will clearly indicate how the invention can be carried into practice.

In the drawings: 15 Fig. 1 is a partial axial section of a pump (having five rotary cylinders) combining the devices forming the subject matter of the present invention (adjustment of the eccentricity, rotating distributor, guiding of the 20 pistons).

Fig. 2 is an end view and partial section, on the side where takes place the control of the variation of the cylinder charge.

Fig. 3 is a half cross section, on the left 25 hand side, made through the plane common to the axes seen through the axis of the cylinders and pistons and a half section, on the right hand side, made through the driving finger of the movable eccentric.

Fig. 4 is a detail view of the system of 30 link and small guide links which characterizes the invention.

Fig. 5 shows another form of construction of this guide system.

Fig. 6 is a cross section of a modification 35 in which the guide system is applied to a pump or motor having fixed cylinders and a simple non-adjustable eccentric.

Fig. 7 is a partial axial section corre- 40 sponding to Fig. 6.

Fig. 8 illustrates a constructional modi- 45 fication in which several groups are mounted in parallel according to a known method.

In Figs. 1 to 3, 1 designates a shaft adapt- 50 ed to actuate the pump; this shaft can rotate when suitable power is applied thereto.

When the device operates, on the contrary, 55 as a motor, the shaft 1 transmits the power supplied by the device to any other device to be actuated.

2 designates a plate angularly rigid with the shaft 1 and concentric with the latter.

3 designates a bearing constituted, in the 60 example illustrated, by a ball bearing; 4 is a cheek supporting this bearing.

5 designates the body of the cylinders angularly rigid with the plate 2 and, consequently, with the shaft 1.

6 is a fixed shaft coaxial with the shaft 1. 65 7 is a first eccentric rigid with this shaft 6.

8 is a bearing constituted, in the example 70 illustrated, by a ball bearing; this bearing allows the free rotation of the structure mov- 75 able on the eccentric 7 and, consequently,

the rotation of 1, 2 and 5 about the fixed shaft 6.

9 is another bearing, similar to the bearing 8 and fulfilling the same function.

10 is a second eccentric movable about the 70 eccentric 7 so as to cause the resulting ec- centration to vary.

11 is a bearing (a roller bearing in the example shown).

12 is an annular raceway capable, owing to 75 the presence of the bearing 11, to freely rotate on the eccentric 10.

13, 13^a-13^d are the rollers of a guide sys- 80 tem which will be described later on (Figs. 4 and 5); these rollers guided by the raceway 12 are rigid with small links shown at 14, 14^a-14^d.

These rollers can be replaced by ball or 85 roller bearings or by shoes according to the mode of application and without departing from the scope of the invention.

15, 15^a-15^d are the links of the pistons 16 to 16^d movable respectively in cylinders 17 to 17^d.

Each of these cylinders is closed by a plug 90 18 forming a head for the piston 17.

19 designates one of the pipe lines causing 95 the cylinders to communicate with the distributor.

20 (Fig. 1) is a plug; 21 is one of the 100 needle screws or blow-through devices (to which access may be had by unscrewing the plug 20); these blow-through devices allow the evacuation of the air when putting the system in service.

22 is a casing to which is secured the 105 cheek 4 and 23 is a cheek secured to the casing 22.

25 and 26 are obturating washers adapted 110 to avoid leakage.

27 designates the distributor about which 115 rotates the body 5 of the cylinders.

28 is a first annular chamber forming a 120 delivery chamber when the device operates as a pump, and an exhaust chamber when the device operates as a motor.

29 is a second annular chamber corre- 125 sponding to the suction in the case of opera- tion as a pump, and to the admission in the case of operation as a motor.

30 is a pipe line communicating with the 130 chamber 28; 31 is a second pipe line com- municating with the chamber 29.

32 is a key securing the distributor on a 135 tubular shaft 33, which can rotate on the fixed shaft 6; the distributor accompanies therefore the angular displacement of the shaft 33, the latter terminating in a finger 34.

35 is a notch formed in the eccentric 10 and driven by the finger 34 when the tubular 140 shaft 33 is actuated.

36 is a worm wheel angularly rigid with the tubular shaft 33.

37 is a system for securing the wheel 36 on the shaft 33.

38 is a casing forming a cheek and secured on the cheek 23.

39 is a cheek secured on this casing 38.

40 is a key rendering the shaft 6 angularly rigid with the fixed cheeks 39, 38, 23, 22 and 4; this key prevents any rotary movement of the shaft 6.

41 is a nut with a lock-nut securing the shaft 6.

10 42 is a cup leather adapted to avoid leakage of liquid outside the chamber 29.

43 is worm gearing with the toothed wheel 36 and operated by a hand-wheel 44.

This driving system can be replaced, without departing from the scope of the invention, by any other suitable system, such as a lever for instance.

The wheel 36 can also be driven by means of an auxiliary motor, thus ensuring the

20 automaticity of this drive, if necessary, the auxiliary motor being then driven by means of manometric or dynamometric relays or by any other suitable member.

The operation of the device used as a pump 25 will now be described:

If the shaft 1 is caused to rotate by a suitable power, it drives in its movement the plate 2 which in its turn drives the body 5 of the cylinders 17; consequently the cylinders take a movement of rotation about the fixed shaft 6.

It will first be assumed that the relative arrangement of the eccentrics 10 and 7 corresponds to the maximum eccentricity which can be obtained (as it has been assumed in the drawings); in this case, the pistons 16 to 16^a, radially urged by the eccentric and guided for instance by a device similar to that which will be described later on, effect upon each revolution, in their respective cylinders, a compression stroke and a suction stroke; the common length of these two strokes is a function of the resulting eccentricity between 7 and 10.

45 If it is now assumed that, by acting on the hand wheel 44 which drives the worm 43 and the wheel 36, the tubular shaft 33 is caused to rotate, the eccentric 10 will be driven in this movement of rotation, owing to the action of the finger 34 on the notch 35 formed in the eccentric 10; considering this latter is also out of center on the eccentric 7, when one half revolution will thus have been effected, the generating line situated at the maximum point of eccentricity of 10 will coincide with the generating line situated at the minimum point of eccentricity of 7. At this moment, the eccentric 10 will be coaxial with the shafts 1 and 6. The 50 pistons will no longer be subjected to any radial displacement and, consequently, the outflow of the pump will be reduced to zero. It will be easily understood that between these two extreme relative positions of the eccentrics 7 and 10, it will be possible to

adopt any of the intermediate positions; thus, the outflow can pass, in an absolutely progressive manner, from zero to its maximum value.

It will also be understood that the more the value of the effective eccentricity is diminished, the more the crank arm formed by the eccentric relatively to the shaft 1 diminishes in length; consequently, the stress on the pistons and with this stress, the pressure produced by the pump will increase in the same proportions.

It will therefore be seen that it is possible, whilst applying to the driving shaft 1 a constant torque, to obtain a variable pressure and outflow, functions reverse from each other, this variation being obtained in a very simple manner by acting on the hand wheel 44.

In the case of operation as a motor, for a constant pressure supplied to the inlet chamber 29, it is possible to obtain a range of progressive speeds from a minimum speed corresponding to the maximum eccentricity, to a maximum speed corresponding to the point for which the eccentricity is minimum.

It is necessary to insist on the fact that the distributor 27 is secured on the tubular shaft 33 and that it moves with the latter when a modification of the value of eccentricity is effected; it has been explained in the preamble that it is necessary that these parts should be rigid together as, upon operation of the eccentric, the dead centers of the system move according to an extent equal to the angular displacement of the eccentric, the movement being circular. The applicant is aware that the mode of operation which has just been described, is known in its general lines and that it is applied to hydraulic pumps and motors.

However, in the device forming the subject-matter of the present invention, the character of novelty resides not only in the fact that the eccentric members do not rotate, and that, by this very fact, the balancing of the system is perfectly ensured, but moreover, and particularly, in the fact that for each position of the movable eccentric, the distribution remains automatically regulated.

It has been seen that in this device the eccentricity is ensured by rotation of a cylindrical member on another cylindrical member; considering all the points of the periphery of these two members remain in contact, a rational distribution of the stresses transmitted is constantly ensured.

In the example described it has been assumed that the eccentricity can vary from zero to a maximum.

Likewise, by devising the eccentrics in such a manner that one of them has a value of eccentricity greater than that of the other,

it will be possible to obtain by one half-revolution of the movable eccentric and by starting from the maximum stroke, another maximum stroke, in reverse direction, by passing 5 through a point where the eccentricity will be null; thus it will be possible to obtain the reversal of the direction of circulation of the fluid in the pipe lines leading to the apparatus.

10 We shall now describe the guide system for the pistons.

It is to be noted that if the pistons simply rested on the raceway and were provided with rollers in the said raceway, they would 15 be subjected to a reciprocating movement the extent of which would be equal to the amplitude of the movement of translation imposed by the eccentric 10.

However, during their stroke, these pistons 20 tons would be moreover subjected to a force which is itself a function, on the one hand, of the amplitude of this movement and, on the other hand, of the pressure of the fluid delivered; it will thus be understood that 25 the wear of the cylindrical bodies and of the pistons would be rapid. This wear might be attenuated by providing these pistons with links directly engaged by a crown replacing the raceway 12; for avoiding the reversal of 30 the links, one of them should then be directly connected to this crown; this device is known and commonly applied.

Notwithstanding these arrangements, the links would take back, in the greater portion 35 of their stroke, an oblique position relatively to the axis of the pistons; the force urging these pistons being at right angles to their axis, both forces will have a resultant which will still tend to apply the piston 40 against the wall of the cylinder according to one of their generating lines, so that the wear of the cylinders will still be very rapid; for practically attenuating this wear, it will be necessary to diminish the value of the 45 above mentioned resultant and, for that purpose, to diminish the value of the maximum angle formed by the axis of the link during its displacement, relatively to the axis of the piston.

50 One would thus be led to provide relatively long links, which would determine an increase of the cumbersomeness and of the weight. These two solutions are known and currently applied, they have been recalled 55 here only for comparison in order that the advantageous features of the present invention may more clearly appear. The said invention suppresses in fact the prejudicious effects mentioned, and this by the following 60 arrangement (see particularly Figs. 4 and 5).

The small link 14-14^a of each piston is pivoted at 47-47^a on an axis rigid with the body 5.

65 It bears on the raceway 12 in which it is

guided by the rollers 13. Each of the axes of these rollers or of any other suitable equivalent device, approximately coincides with the axis of the piston 16 corresponding to this small link; the link 15 is itself enclosed 70 at the above mentioned point of coincidence, by means of a spherical member R¹ secured by the members 48 and 49 and the screws 50, 51.

The link 15 is itself connected to the piston 6 by means of a second spherical member R² held in its housing, for instance by means of a screw 56. Without departing from the scope of the invention, the ball joints R¹ and R² might quite as well be replaced by axes and rings, or by any other device fulfilling the same function. It will be understood 80 that the oscillating movement of each of the links will be very small; it will have for amplitude one half the pitch of an arc the chord of which will be a function of the piston stroke and of the radius described by the small link 14, which radius is itself function of the distance between the axis 47 and the fulcrum of the rollers on the raceway. 90

By way of example, if one considers a piston stroke of 20 millimeters and a link of 40 millimeters in length, with various known systems of assemblage which have been recalled above, the maximum angle, previously mentioned, is equal to 12°.

If, on the contrary, the device in accordance with the invention is used, by maintaining the same values for the piston stroke and the length of the links, and if use is made of a small link having 90 millimeters between axes (between rollers and pivoting points), the maximum value of the said angle is reduced to 1°5'; the resultant tending to apply the piston against the cylinder, and, consequently, the causes of wear of the latter are reduced in the same proportions. These data show the considerable practical advantage of the device illustrated. 110

Fig. 5 shows, by way of example, another form of construction of the small links. In this modification, each small link 14 pivots within a ring 52 maintained in the body 5. Its opposite end is tubular and the spherical member R¹ is held in place by the screw 55. 115

Figs. 6 and 7 illustrate the application of this guide system to a pump (or motor) having fixed cylinders.

In these figures:

61 is a shaft adapted to receive the energy for actuating the pump;

62 is an eccentric rigid with this shaft;

63 is a double circular raceway centered on the eccentric 62;

64 and 65 are ball or roller bearings allowing the rotation of the eccentric 62 within the raceway 63.

As previously:

14 to 14^a are small guide links respec- 130

- tively pivoted by axes 47 to 47^a on the fixed frame 75 of the cylinders; 13 to 13^a are rollers respectively rigid with these small links; 15 to 15^a are the links connecting the pistons 16 to 16^a to the small links; In the same figures: 72 to 72^a are plugs forming cylinder heads; 73 is one of the pipe lines feeding the cylinders; 74 designates one of the blow-through devices adapted to evacuate the air at the time the apparatus is put in action. 75 is the frame in which are bored the cylinders and channels. 76 is a cheek of this frame, forming a bearing; 77 is another cheek acting as an obturator for the distributor; 78 is the body of the distributor; the latter is driven in rotation by the shaft 61, by means of the square part 79 on which it is freely mounted in the longitudinal direction. This square member can also be in the shape of an Oldham joint or of any other similar driving device; 80 is the delivery orifice and 81 the suction orifice of the apparatus; 82 is a spring ensuring fluid-tightness between the rotary distributor and the frame; 83 is an intermediate washer adapted to facilitate the rotation of the distributor 78 at its points of contact with the frame 75; 84 is a cup leather adapted to ensure the fluid-tightness of the distributor; 85 is a stuffing-box adapted to ensure the fluid-tightness of the pump and to thus avoid the projection of liquid to the exterior; 86 and 87 are ball or roller bearings ensuring the free rotation of the shaft 61; these elements can be replaced by any other device capable of fulfilling the same function.
- Finally, Fig. 8 shows a modification in which the standard assemblage of Figs. 1 to 5 is applied to a pump composed of two groups of cylinders, or more, operating in parallel; in this figure have been shown three cylinders 17, 17', 17'' operating in parallel; if the outflow of a cylinder is equal to a value D, the total outflow of the group is equal to 3D. This mode of grouping is moreover known and it is mentioned here only by way of example of application of the invention. Likewise, the number of cylinders of one and the same group and the arrangement of these cylinders may vary.
- It is to be understood that various accessory modifications can be made in the devices described by way of example. All the modifications thus obtained are included within the scope of the invention if they apply the principle of the same such as set forth in the foregoing description and in the following claim.
- I claim:—
- In a system of hydraulic pumps, motors or similar apparatus, multiple radial cylinders of the type in which the stroke of the pistons is controlled by an eccentric, this system comprising a rotating annular body wherein radial cylinders are hollowed out, which communicate with the inner periphery of the annular body and include pistons having rods, guiding links connected to the piston rods and connected to the rotating body, a device comprising a circular eccentric for driving the said pistons, a raceway carried by said eccentric and consisting of two rings spaced apart, spherical members for connecting the piston rods to the pistons, other spherical members for connecting the piston rods to the guiding links, rollers carried by each of the said guiding links and engaging in the circular channel formed by the rings constituting the raceway.
- The foregoing specification of my improvements in hydraulic pumps and motors having radial fixed or rotary cylinders signed by me this 6th day of July 1928.
- GEORGES CUTTAT.
